DESIGN FOR A PARKING METER CASING

Robert F. Broussard, Houston, Tex., assignor to
Duncan Meter Corporation, Chicago, Ill., a cor-
poration of Illinois

Application June 27, 1947, Serial No. 139,967

Term of patent 14 years

(Cl. D52—3)

To all whom it may concern:

Be it known that I, Robert F. Broussard, a citizen of the United States, residing at Houston, in the county of Harris and State of Texas, have invented a new, original, and ornamental Design for a Parking Meter Casing, of which the following is a specification, reference being had to the accompanying drawing, forming part thereof, wherein:

Fig. 1 is a top plan view of a parking meter casing, showing my new design;

Fig. 2 is an elevational view looking toward one side thereof; and

Fig. 3 is an elevational view looking toward another side thereof removed 90° distant from the side shown in Fig. 2.

I claim:
The ornamental design for a parking meter casing, as shown.

ROBERT F. BROUSSARD.
